JOSEPH V. DURNIN, OF ALLENTEWON, PENNSYLVANIA

THERMOSTATIC DEVICE

Application filed August 28, 1931. Serial No. 559,966.

My invention relates to a thermostatic device for actuating a movable element.

The invention is well adapted to be used in connection with a gas burner for automatically cutting off the flow of gas when the flame is extinguished, while not necessarily restricted to this use.

In the accompanying drawings,

Figure 1 is a plan view of apparatus embodying my invention,

Figure 2 is a side elevation of the same,

Figure 3 is a transverse vertical section taken on line 3—3 of Figure 2, parts omitted,

Figure 4 is a similar view taken at a right angle to Figure 3,

Figure 5 is an edge elevation of a modified form of thermostatic device embodying the invention,

Figure 6 is an elevation at a right angle to Figure 5, parts being shown in vertical section.

In the drawings, wherein for the purpose of illustration is shown a preferred embodiment of my invention, the numeral 10 designates a gas burner element, preferably of the annular type, having a central passage 11. The numeral 12 designates a pilot light. The numeral 13 designates a gas supply pipe line, having a branch pipe 14 connected therein, equipped with the usual manually operated cut-off valve 15. The outlet end of this branch pipe discharges into the air mixing inlet 16 of the burner, which is in communication with the interior of the burner element 10, as is customary. A valve casing 17 is connected in the branch pipe 14, and embodies a valve seat 18, to be engaged and disengaged by a downwardly seating valve element 19, connected with a valve stem 20.

The numeral 21 designates a generally U-shaped tubular element included in the thermostatic device, and this tubular element embodies a short arm 22, vertically arranged, and cylindrical throughout the major portion of its length. The tubular element embodies a long vertical arm 23, which is preferably circular in cross-section and tapers downwardly, providing a reduced portion 24, in communication with the lower end of the short arm 22. The long arm 23 is pref-

erably provided with corrugations or fins 25, for effecting proper heat transfer. The long arm extends through the central passage 11, and preferably projects a slight distance above the burner element 10. The valve casing 17 is provided with a depending boss or plug 26, exteriorly threaded for engagement with the upper threaded end of the short arm 22, as shown. The arm 22 is provided with a plurality of vent openings or ports 27, for placing the interior of the arm 22 in communication with the atmosphere. These ports are arranged immediately beneath the plug 26, as shown.

The valve stem 20 is freely slidably mounted and projects downwardly into a recess 28, formed in the plug 26. Packing 29 surrounds the valve stem within the recess, to prevent leakage of gas, and a washer 30, such as a copper washer, is arranged beneath the packing. A compressible coil spring 31 surrounds the lower end of the valve stem, and engages a plunger 32, having screw-threaded engagement upon the lower end of the valve stem, and, accordingly, longitudinally adjustable thereon. The valve element 19 has a groove 33 formed in its top, for receiving the end of a suitable tool for turning the same, access being had to the valve element by removing a plug 34. By this means, the plug 34 may be removed, and the valve element 19 turned to grind the same upon its seat, or it may be rotated to longitudinally adjust the plunger 32 upon the valve stem. Further adjustment may also be effected by turning the valve casing 17 upon the short arm 22. By this means, the elements may be so adjusted that the valve element will open and close at a selected temperature.

Arranged within the short arm 22 is a float 35, preferably formed of a copper shell, although the same may be formed of cork or any other material that will float. This float element has a loose fit within the tubular arm 22, for a purpose to be described. The tubular element has its long arm 23 filled with mercury 36, or any other liquid having a high thermal expansion, and a small quantity of enclosed air between the inner top of tube 23 and the high thermal liquid. This liquid

also extends into the lower portion of the short arm 22, with the float 35 resting thereon. The float 35 has a substantially smaller diameter than the interior of the arm 22, which prevents any possibility of the float sticking, due to expansion, and also permits of atmospheric pressure passing through the ports 27, and acting upon the surface of the mercury 36 within the short arm 22. This atmospheric pressure upon the surface of the mercury within the short arm serves to retain the mercury and the enclosed air within the top of the long arm 21. Should the mercury become unduly heated by accidental cause, or the like, and thereby unduly expand or vaporize, the pressure is relieved by such mercury passing the float 35, then shifted to the uppermost position, and thence escaping through the ports 27.

In Figures 5 and 6, I have shown a slight modification of the invention. The long arm 21 is shown adjustably connected with the short arm 22, through the medium of a coupling 22', which permits of the long arm 21 being angularly adjusted or swung to an inclined position with relation to the horizontal, as shown in dotted lines, Figure 5. When the arm 21 is inclined from the vertical, the mercury and enclosed air upon being heated, functions slower to raise the float 35, than it does when the arm 21 is vertical, in the upper position.

The operation of the apparatus is as follows:

When it is desired to light the burner element, the valve 15 is opened, while valve element 19 is closed, due to the action of the spring 30. The pilot light 12 is now actuated to project a flame upon the top of the long arm 21. This flame heats the enclosed air and mercury within this arm, which immediately expands, raising the float 35 which, in turn, engages the plunger 32, thereby opening valve element 19. The gas will now pass to the burner element 10, and this gas is ignited in the usual manner, by the flame from the pilot light. The enclosed air and mercury within the arm 23 is maintained suitably heated and expanded, by radiating heat from the burner element 10, whereby the float 35 is held at the uppermost position, and valve element 19 retained open. Should the flame at the burner element become extinguished, the mercury immediately cools and contracts, thereby automatically causing the valve element 19 to close and cut off the flow of gas from the burner element. Actual tests which I have made show that the valve element may be rapidly opened by projecting the flame upon the top or upper portion of the arm 21, which this action decreases in rapidity if the flame is applied to the lower portion of the arm 21. Also the action is more rapid when the long arm 21 is in a vertical position. Of course, the invention is, in no sense, restricted

to arranging the arms 20 and 21 in a vertical position.

The mercury readily expands upon being heated, but the enclosed or entrapped air has a greater co-efficient of expansion. The mercury not only serves as an expanding element but also as means to provide a liquid seal to prevent the escape of the expanding air. The mercury also has a high specific gravity whereby it will raise the float more effectually, and will also cause the float to properly unseat the valve element.

I have found that as the long arm of the tubular element is inclined toward the horizontal, that the action is slower, and a higher degree of heat is required to cause the enclosed air and expansible liquid to function for lifting the float, with a corresponding length of time for the reverse movement of the float, due to the increased length of time required for the enclosed air and mercury to cool, which must be heated to a higher temperature. I, therefore, contemplate regulating the degree of heat at which the device will function by angularly adjusting the long arm of the tubular element from the vertical. The device cannot be properly used in connection with the particular type of burner shown when angularly adjusted, but may be used for various other purpose, as shown in Figures 5 and 6.

The invention is, in no sense, restricted for use in connection with the burner element, as it may be used for any purpose where it is desired to employ thermostatic means for operating a movable element. The device may be used to open or close a valve, or to actuate any other means.

It is to be understood that the form of my invention herewith shown and described is to be taken as the preferred example of the same, but that various changes may be made in the shape, size and arrangement of parts, without departing from the spirit of the invention or the scope of the subjoined claims.

Having thus described my invention, what I claim is:

1. A thermostatic device comprising a generally U-shaped tubular element including an arm closed to the atmosphere and an arm open to the atmosphere each arm being rigid throughout its length, a high thermal expansion fluid held within said arms, a float loosely mounted within the open arm so that atmospheric pressure may act upon the fluid held within said arms, means actuated by the float, and a swivel joint capable of being turned to a desired position and retained therein connecting the lower ends of the arms so that one may be angularly adjusted with relation to the other.

2. The combination with a burner having a passage, of a generally U-shaped tube including arms, one arm being closed at its free end and extending into the passage, the

co-acting arm being provided near its free end with an aperture leading to the atmosphere, means for supplying gas to the burner including a valve embodying a valve casing and valve element, the valve casing being mounted upon the free end of the co-acting arm in a manner to leave the aperture uncovered, a float arranged within the co-acting arm to actuate the valve element, and a high thermal expansion fluid arranged within the generally U-shaped tube.

3. The combination with a valve embodying a valve case and valve element, of a thermostatic device for co-action therewith, comprising a generally U-shaped tube including arms, one arm being closed at its free end and the co-acting arm being open at its free end and provided with an aperture at a point near and spaced from such free end, a plug secured to the valve case and extending into the free end of the co-acting arm and having screw-threaded engagement therein so that a relative longitudinal adjustment may be effected between the valve case and co-acting arm, a float arranged within the coacting arm to actuate the valve element, and a high thermal expansion fluid arranged within the generally U-shaped tube.

30 4. The combination with a valve embodying a valve case and valve element, said valve case having an attaching part, of a thermostatic device for coaction with the valve, comprising a generally U-shaped tube 35 including arms, one arm being closed at its free end and a co-acting arm being open at its free end and provided with an aperture at a point near and spaced from such free end, the free end of the co-acting arm being longitudinally adjustably mounted upon the attaching part, a float arranged within the co-acting arm to actuate the valve element, and a high thermal expansion fluid arranged within the generally U-shaped 40 tube.

45 5. The combination with a valve embodying a valve case and valve element including a stem, said valve case having an attaching part, a plunger longitudinally adjustably mounted upon the stem and projecting beyond said attaching part, a U-shaped tube embodying arms, one arm being closed at its free end, the co-acting arm having connection with the attaching part and provided 50 with an aperture beneath the attaching part, the plunger being arranged within the co-acting arm, a removable plug for the valve case to afford access to the valve element for effecting the adjustment of the plunger upon 55 the stem, a float within the co-acting arm, and a high thermal expansion fluid arranged within the generally U-shaped tube.

60 6. The combination with a valve embodying a valve case and valve element, said valve case having an attaching part, of a thermo-

static device for co-action with the valve, comprising a generally U-shaped tube including arms, one arm being closed at its free end and a co-acting arm, the free end of the co-acting arm being longitudinally adjustably mounted upon the attaching part, said co-acting arm having a port associated therewith which leads to the atmosphere, a high thermal expansion fluid arranged within the generally U-shaped tube, and a float 70 75 loosely mounted within the coacting arm to actuate the valve element.

In testimony whereof, I affix my signature.
